CLAIM

The ornamental design for a set of instrument panel plates, as shown and described.

DESCRIPTION

FIG. 1 is a front view of a set of instrument panel plates according to my novel design; and,

FIG. 2 is a top view of a set of instrument panel plates according to my novel design.

The dash line included depicts environment and is not part of the claimed design.

The sides of the set of instrument panel plates are plain and unornamented and the bottom of the set of instrument panel plates is understood to follow the same contour as shown in FIG. 1.
